(57) **CLAIM**

The ornamental design for a marine electronics display device, as shown and described.

DESCRIPTION

FIG. 1 is a front perspective view of a marine electronics display device in accordance with the present invention; FIG. 2 is a front view of the marine electronics display device of FIG. 1;

FIG. 3 is a rear view of the marine electronics display device of FIG. 1;

FIG. 4 is a left side view of the marine electronics display device of FIG. 1;

FIG. 5 is a right side view of the marine electronics display device of FIG. 1;

FIG. 6 is a bottom view of the marine electronics display device of FIG. 1;

FIG. 7 is a top view of the marine electronics display device of FIG. 1; and,

FIG. 8 is a front perspective view of the marine electronics display device of FIG. 1 shown mounted in a bracket.

The dot-dash broken lines delineate the bounds of the claimed design. The dash-dash broken lines depict environment and form no part of the claimed design.

1 Claim, 8 Drawing Sheets
